Howson & Howson

UNITED STATES PATENT OFFICE.

FRANK SOLEY, OF PHILADELPHIA, PENNSYLVANIA, ASSIGNOR TO MILLER LOCK COMPANY, OF PHILADELPHIA, PENNSYLVANIA, A CORPORATION OF PENNSYLVANIA.

PADLOCK.

1,300,037.

Specification of Letters Patent.

Patented Apr. 8, 1919.

Application filed February 13, 1919. Serial No. 276,758.

To all whom it may concern:

Be it known that I, FRANK SOLEY, a citizen of the United States, residing in Philadelphia, Pennsylvania, have invented 5 certain Improvements in Padlocks, of which the following is a specification.

My invention relates to certain improvements in padlocks for which a patent was granted to me on the eighth day of June, 10 1915, No. 1,142,638.

One object of my invention is to improve the construction of the lever which acts as a dust guard at the opening in the body of the lock and at the same time engages the 15 heel of the shackle, when the shackle is closed.

A further object of the invention is to dispense with the tubular pivot for the lever and to provide means whereby the lever can be held in position on its short pivot, allowing 20 clearance of the spring.

In the accompanying drawings:

Figure 1 is a side view, partly in section, illustrating the body of the lock and the 25 shackle in its raised position;

Fig. 2 is a sectional view, showing the shackle closed and locked by the bolt;

Fig. 3 is a sectional view on the line 3—3, 30 Fig. 2;

Fig. 4 is a detached perspective view of the bolt;

Fig. 5 is a detached perspective view of the lever;

Fig. 6 is a detached perspective view of 35 one of the tumblers;

Fig. 7 is a detached perspective view of the spring which throws the bolt;

Fig. 8 is a detached perspective view of the shackle spring; and

Fig. 9 is a view of the lock casing with 40 all of the mechanism removed with the exception of the bolt and lever.

My invention relates particularly to improvements in padlocks and the design of 45 the casing may vary without departing from the essential features of the invention. While I have shown the lock with four tumblers, a greater or less number of tumblers may be used.

1 is the casing of the lock made in two parts connected together by rivets in the ordinary manner. 2 is the shackle pivoted at 3 to the body of the lock and having at its opposite end a nose 4 notched at 5 for the

reception of the bolt when the shackle is in 55 the closed position, as in Fig. 2. The bolt 6 is made as shown in Fig. 4 and has a horizontal portion 7 forming the bolt proper, which is of such thickness as to enter the notch 5 in the shackle, as shown in Fig. 2. 60 This bolt is notched at 8 and 9 and is arranged to slide on the pins 10 and 11 projecting from the casing 1. A spring 12, Fig. 7, is mounted on the pin 10 and one arm 13 of this spring extends back of a lug 14 on the bolt, while the other end 15 rests on a lever 17 pivoted at 18 to a pin projecting from the casing. This spring not only tends to throw the bolt, but also tends to raise the lever into the position illustrated in Fig. 1 where the horizontal portion 19 of the lever 70 closes the shackle opening in the casing so as to prevent dust entering the casing when the lock is open. This lever 17 also has a projection 20 which is substantially the same 75 height as the portions 16 and 19 and bears against the casing of the lock so as to prevent the lever tilting on the short pivot pin 18. The lever also has a portion 21 bent in the opposite direction from the portion 20, 80 which is arranged to engage the heel 22 of the shackle when the shackle is in the closed position, as shown in Fig. 2, so that while the nose of the shackle is held by the portion 7 of the bolt, the heel of the shackle is held 85 by the projection 21 of the lever, making what is termed a "double" lock.

A coiled spring 23 is hooked onto the projection 16 of the lever and onto a pin 24 at the heel of the shackle. This spring moves 90 the shackle to its open position, as shown in Fig. 1, when the shackle is released by the bolt and also places tension on the lever when the shackle is in the closed position, tending to hold the projection 21 of the lever 95 in contact with the heel of the shackle.

In order to lock the lever, when its projection 21 bears against the heel 22 of the shackle, I provide a projection 30 on the bolt, which rests under the projection 21 100 of the lever, holding it in such position that it cannot be released without turning the key and withdrawing the bolt. The moment the bolt is withdrawn, the lever is free to turn on its pivot.

25 is the fence of the bolt adapted to enter the notches 26 in the tumblers 27, which are mounted on the pin 11 and have springs 28

bearing against the pin 29. It will be understood that the number of notches in the tumblers may be varied and the shape of the tumblers may also be varied, if desired.

5 Notches may also be provided in the tumblers for a master key.

31 is a key hub adapted to receive a key. The pins 3, 10, 11, 29 and 32 project from one section of the casing and through openings in the other section and are riveted so as to hold the two sections firmly together. Several of these pins also act as pivots for the mechanism.

It will be seen on referring to Fig. 2, that 15 when the shackle is closed the portion 7 of the bolt 6 enters the nose of the shackle, while the portion 21 of the lever rests against the heel of the shackle so that the shackle is doubly locked. By making the 20 lever in the manner shown in Fig. 5, I can use a very short pivot pin 18 and can hold the lever from twisting by the projecting portions 16, 19 and 20. By making the short 25 pivot pin 18, I allow sufficient room for the spring 23 so that it has a direct pull when the shackle is moved from the open to the closed position, and vice versa.

I claim:

1. The combination in a padlock, of a 30 casing; a shackle pivotally mounted in the casing; a bolt arranged to engage the nose of the shackle; a lever pivoted to the casing and having an arm located in the path of the nose and of a shape to close the opening in 35 the casing when the shackle is raised, said lever having another arm arranged to engage the heel end of the shackle, the bolt, when in the locked position, also engaging the lever and preventing its withdrawal 40 from the heel of the shackle; a short pivot pin for the lever; and a spring attached to a projection on the lever and to the heel of the shackle.

2. The combination in a padlock, of a 45 casing; a shackle pivoted thereto and notched at its nose end; a sliding bolt mounted in the casing and having a portion arranged to enter the notch in the nose end of the shackle; a pivoted lever having a

projection at the rear arranged to engage 50 the heel end of the shackle, when the shackle is closed, and having a portion arranged to close the opening for the nose end of the shackle, when the shackle is in the open position, and also having projections of substantially 55 the same height so as to bear against the casing; a short pivot pin for the bolt; and a spring extending from one of the projections of the lever to the heel of the shackle, said spring extending over 60 the pivot pin.

3. The combination in a padlock, of a casing; a shackle pivotally mounted in the casing; said shackle having a notched nose end; a sliding bolt mounted in the casing 65 and having a projecting portion arranged to enter the notch in the shackle; two pins on which the bolt slides; a coiled spring mounted on one of said pins, one end of said spring bearing against the bolt and tending 70 to move it forward; a lever pivoted to the casing and having a projecting portion against which the other element of the spring rests; and a coiled spring extending from said projection to the heel of the 75 shackle, the lever having a plate portion which closes the shackle opening when the shackle is raised.

4. The combination in a padlock, of a 80 casing; a shackle pivotally mounted in the casing; a bolt arranged to engage the nose of the shackle, said bolt having a projecting lug at its forward end; pins on the casing for engaging the bolt; a lever pivoted to the casing and having an arm located in the 85 path of the nose of the shackle and of a shape to close the opening in the casing when the shackle is raised, said lever having another arm arranged to engage the heel of the shackle; a spring mounted on one of the 90 guide pins of the bolt, one arm of the spring engaging the lug on the forward end of the bolt, the other arm of the spring engaging the lever; and a spring extending from the lever to the heel of the shackle. 95

In witness whereof I affix my signature.

FRANK SOLEY.
